S. CARLSON

COMB FOR LONG BOBS

Filed April 12, 1928

Inventor:

Signe Carlson.

By Wm F. Freudreich,

Atty:

UNITED STATES PATENT OFFICE.

SINGE CARLSON, OF CHICAGO, ILLINOIS.

COMB FOR LONG BOBS.

Application filed April 12, 1928. Serial No. 269,329.

The present invention relates to hair combs and has for its object to produce a simple and novel device for securely holding together strands of hair brought to the back 5 from opposite sides of the head. In other words, the present invention may be said to have for its object to produce a hair holding device that will permit a woman's hair to be cut short in the back, while the hair at the 10 sides and on the top of the head is comparatively long so that the ends may be gathered together at the back of the head and held in place by a single device.

The various features of novelty whereby 15 my invention is characterized will herein-after be pointed out with particularity in the claims; but, for a full understanding of my invention and of its objects and advantages, reference may be had to the following 20 detailed description taken in connection with the accompanying drawing, wherein:

Figure 1 is a view of the back of the head of a woman whose hair is being held in a comb or holder arranged in accordance with 25 my invention; Fig. 2 is a top plan view, on a larger scale than Fig. 1, of the comb detached from the hair; Fig. 3 is a section taken on line 3—3 of Fig. 2, showing the comb in its closed condition; Fig. 4 is a view 30 similar to Fig. 3, showing the comb partially open; and Fig. 5 is a back view of the central portion of the comb, with the ornamental cover plate for the hinge raised.

My improved device consists of two comb-like elements curved to fit the shape of the 35 head. These elements are arranged back to back and secured together at their middle by a spring hinge that tends constantly to hold the ends of the backs in contact with each 40 other, but permits them to be swung apart.

In the drawing the backs of the combs are in the form of long curved bars 1 and 2. These bars are hinged together, midway between their ends, by means of a spring hinge 45 3. An ornamental flap 4 is hinged to the upper bar in such a position that, when the comb is in use, the flap will swing down and conceal the spring hinge, as in Fig. 1. The lower bar is provided with a short rear- 50 wardly projecting finger piece 5 just below the spring hinge. When the ornamental flap is swung up as indicated in Fig. 4, a thumb may be placed under the finger piece 5, and the forefinger of the same hand on the upper end of the flap, and pressure be ap-

plied to open the device by swinging the bars from the relative positions shown in Fig. 3 to those which they occupy in Fig. 4.

The teeth of the two comb devices are of peculiar shape, being in the form of U-shaped wires 6. One leg of each wire in the upper section is fastened to the top of the upper bar 1, while the other leg extends downwardly in front of the bar. In the same way, one leg of each wire constituting a 65 tooth in the lower section is fastened to the under-edge of the lower bar 2, while the other leg extends upwardly in front of the bar. The plane of each U-shaped tooth, that is the plane containing both legs thereof, 70 preferably extends radially with respect to the center of curvature of the comb as a whole. Furthermore, the free legs of the teeth are made of such lengths that the lower ends of those in the upper half or section extend downwardly past the upper ends of the free legs of the teeth in the lower half or section of the device. Furthermore, the teeth are preferably so disposed that there is little or no space left between the upper 75 teeth and the lower teeth at the points where they cross each other.

In using the device, it is first opened as shown in Fig. 4; the hair to be held by the comb is brought from the top and sides of 80 the head to the rear; the concave side of the open comb is placed against the head, in contact with the hair to be held; and the device is then allowed to close, the teeth entering 85 the hair from above and below. As the 90 comb closes, the volume of the space in which the hair that has been gripped lies becomes smaller, so that the hair is held not only by a comb action, but by a clamping 95 action.

The manner of using my improved device is shown in Fig. 1. The hair at the back of the head A is cut short, while that at the side and top is comparatively long, so that the sides may be brought together at the 100 rear where it is received by the comb or holding device.

It will thus be seen that my improved device permits a woman to avail herself of the advantage of having hair cut short at the 105 back, while the hair at the sides remains long, without being subjected to the objections to loose long hair. While my improved device is particularly adapted for use in confining the hair cut according to a 110

so-called long bob, it may be used wherever hair is to be held in place by a fastening device.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A hair holder comprising two curved bars overlying each other and secured together at the middle by a spring hinge, the upper bar having fingers extending upwardly and then downwardly on the concave side, and the lower bar having fingers extending

downwardly and then upwardly on the concave side and projecting past the free ends 20 of the fingers on the upper bar when the holder is closed.

2. A hair holder comprising two curved bars overlying each other and secured together at the middle by a spring hinge, teeth 25 extending from the upper edge of the upper bar and the lower edge of the lower bar and bent laterally until the upper and lower teeth cross each other on the concave side of the bars when the holder is closed, and a member hinged to the upper bar above and depending over the hinge.

In testimony whereof, I sign this specification.

SIGNE CARLSON
